STEP-ON FLOOR LIGHT

Jack L. Albright, 1619 Edgewood Ave., Racine, Wis.

Filed Feb. 20, 1963, Ser. No. 73,639

Term of patent 3½ years

(Cl. D48—20)

FIG. 3

FIG. 2

FIG. 1 is a front perspective view of a step-on floor light showing my new design.

FIG. 2 is a top plan view of FIG. 1.

FIG. 3 is a right side view of FIG. 2, the left side being the same as the side shown.

The fragmentary showing of an electric cord is for illustrative purposes only.

I claim:

The ornamental design for a step-on floor light, substantially as shown, and described.
